(57) **CLAIM**

The ornamental design for a plant pot, as shown and described.

DESCRIPTION

FIG. 1 is a perspective view of a plant pot showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a perspective view of the in use state; and,

FIG. 10 is another perspective view of the in use state. The broken lines illustrate portions of the plant pot that form no part of the claimed design.

1 Claim, 10 Drawing Sheets
